UNITED STATES PATENT OFFICE.

FRANCIS M. PATTON, OF WASHINGTON, DISTRICT OF COLUMBIA; ETHEL M. PATTON
ADMINISTRATRIX OF SAID FRANCIS MIRA PATTON, DECEASED.

REFRIGERATOR CAR.

Application filed December 16, 1925. Serial No. 75,740.

The present invention relates to refrigerator cars and consists in the provision of means for causing a positive circulation of cold air in an improved and advantageous manner.

Under the present practice, warm air from the body of the car is induced into the top of the ice bunkers by the falling of the chilled air in the bunker and which finally moves out into the storage space of the car from the bottom of the bunkers, thus establishing a natural circulation. This circulation is extremely slow for it is estimated, that under general conditions, the cold air rises about 10% the height of the car in the first twenty-four hours, about 25% in forty-eight hours and about 50% in 72 hours, after which time it rises very slowly. It will thus be seen that cars loaded with highly perishable substances may very often reach their destination before the natural circulation of air has been completed or before any material cooling or refrigerating of the contents has been effected, which has lead to so-called "interior icing," where ice is thrown on or packed with the contents of the car, resulting in the deterioration of the car, and flooding the bottom of the car destroying a considerable part of the cargo. It is also known that some forms of forced circulation have been proposed, but these are not advantageous for numerous reasons, such as, cost of installation, space occupied in the car and system of circulation.

The object of the invention is the reversal of the air current in the ice bunker so as to deposit the heavy cold air on top of the load. The natural and immediate dropping or convection of this air in filtering through the load gives an immediate and even reduction in temperature in the whole load, and will make so-called "interior icing" unnecessary.

It is the further object of the present invention to produce a forced circulation of air through the ice bunkers in each end of the conventional refrigerator car, in a simple, practical and economical manner without reducing the storage space or the space in the ice bunkers.

With these and other objects in view, the invention resides in the sundry details of construction, combination and arrangement of parts shown in the accompanying drawings and will be referred to as the specifica-

tion proceeds, and pointed out in the appended claims.

In this specification and the annexed drawings, the invention is disclosed in the form in which it is considered to be the best, but the invention is not limited to such form because it is capable of being embodied in other forms; and it is to be understood that in and by the claims following the description herein it is intended to cover the invention in whatever form it may embody within the scope thereof.

In the drawings, which show the preferred embodiment of the invention as at present devised:

Figure 1 is a fragmentary longitudinal sectional view of one end of a refrigerator car of the conventional type, equipped with the invention; and

Figure 2 is a vertical sectional view taken on the line 2—2 of Figure 1, looking in the direction of the arrow.

Referring in detail to the drawing, 10 designates the body of a refrigerator car of conventional type provided at both ends 80 thereof with an ice bunker 11. The bunker 11 may be of any suitable construction as the invention may be applied to all types of refrigerator cars without requiring any modification in their construction or in the construction and arrangement of the ice bunker 11.

The ice bunkers 11 are ordinarily provided by a partitioning the end portions of the car with a transverse wall 12 having suitable 90 openings 13 and 14 at their tops and bottoms respectively in order to permit the ingress and egress of air into and from the ice chamber 11. The ice is normally supported by the bottom 15 of the car or on a grating or 95 other suitable support 16.

It is the purpose of this invention to place a battery of fans at or near the bottom of the ice bunkers, the ice being supported above on a grating or other suitable support permitting the passage of air therethrough. The fans are sufficiently large and numerous enough to draw the warm air from the bottom of the car through the opening 14, and to force it upwardly through the ice-load 105 resting on the grating 16, through the opening 13 into the top of the car and to draw the same back again through the contents of the car. The cold air forced through the opening 13 has a natural tendency to descend, 110

but is accelerated by the suction and forcing action of the fans 17, chilling the air and the contents of the car as it descends. The vigorous circulation produced by the 5 fans will cause a constant, even and rapid chilling or refrigeration of the contents of the car.

It will also be observed that with this circulation, the contents in the upper portion 10 of the car, which are ordinarily the warmest, will be chilled first by the air coming from the ice bunkers.

In carrying the invention into practice and for the purpose of the present illustration 15 the fans 17 are shown as horizontally disposed immediately beneath the grating 16 and above the opening 14 in the bottom of the partition 12. These fans are each mounted on a shaft 18 journaled in any suitable manner, such as the bearings 19, whereby the fans may be rotated and held in position.

Rotation of the fans may be effected in any desired manner such as by motors 25 placed beneath the car, or by operatively connecting the same with the running gear of the car, and for the purpose of the present illustration the latter being shown and preferred. The shafts 18 are each illustrated 30 as connected with the running gear through gearing 21 mounted on a transverse shaft 22 journaled in bearings 23, the shaft 22 having a pulley 24 fast thereon. The pulley 24 is connected to a belt or other suitable driving medium passing over a pulley 25 fast on an axle of the running gear of the car. The fans 17 are preferably positioned in openings 26 provided in the usual drain pan 27 disposed under the grating 16, the marginal 35 portions of the openings 26 being upturned to prevent the drainage from passing through the openings; a drain pipe 28 being provided for this purpose.

While the fans are operating, they will 45 intercept a certain amount of the drippings from the ice bunker and will spray the same, which has a further beneficial effect of accelerating the cooling of the air coming into the bottom of the bunker 11 through the 50 opening 14.

When the fans are driven from the running gear of the car, as illustrated, it is of course understood that they will not operate while the car is not in motion and in this 55 case the natural circulation, as is ordinarily depended upon, will be set up; but as soon as the car is again in motion the fans will be operated to establish the forced circulation in reverse direction.

60 The ice bunkers may be filled as usual through the ordinary trap door 29 provided in the upper portion of the car, immediately over the bunkers 11.

It is manifest that in order to accomplish the desired circulation by one set of fans,

the fans 17 must rotate in the same direction regardless of the direction of the movement of the car. This may be effected by any suitable means which is common in the art for this purpose, and for more detail examples reference may be had to the United States Patents Nos. 392,610 and 1,374,523, but for the purpose of the present disclosure a diagrammatic illustration of one type of shifting gearing is shown particularly in 70 Fig. 2. The gearing 21 is such as will automatically shift to effect this result. The shafts 18 each carry a bevel gear *a* which engages with the shiftable gearing, there being a set of shiftable gearing for each fan. 75 This gearing consists of a slideable sleeve *b* on the shaft 22 and having fast thereon a pair of opposed bevel gears *c* and *d* respectively, spaced apart and adapted to be alternately brought into engagement with the gear *a*, on opposite sides of its axis. The alternate shifting of the gears *c* and *d* is effected by a pin *e* projecting from the shaft 22 into the oblique slot *f* in the sleeve *b*. There may be one or more of said pins *e* and 80 slots *f* in each of the sleeves *b*.

It will thus be obvious that when the car is moving in one direction the pin *e* will be moved into one end of the slot *f* and thereby shift the sleeve *b* to bring one of the 85 gears *c* or *d* into engagement with the gear *a*, and then upon a reverse movement of the car the shaft 22 will be rotated in the opposite direction and cause the pin *e* to act on the oblique side walls of the slots *f* to move 90 to the other end of the slots, thereby shifting the sleeve to bring the other gears *c* or *d*, as the case may be, into engagement with the gear *a*. Suitable stops *g* are provided on the shaft for limiting the movement of 95 the sleeve *b*. Only one set of the shiftable gearing has been described, as the other is identical therewith.

It is also to be understood that the shifting of the gearing 21 may be effected by 100 simple manual means in any approved manner as will be readily apparent to those skilled in the art. It is also to be understood that the gearing A, C, and D may be frictional gearing instead of teeth gears as 105 shown, and it is also well within the purview of the invention to use double acting fans which will be successively brought into effective operation upon the reverse movements of the car thereby eliminating a shifting 110 gearing 21.

What I claim is:—

1. The combination with a refrigerator car having an ice bunker therein, said bunker having air communication with the 115 interior of the car at its upper and lower ends, a fan for inducing currents of air from the bottom of the interior of the car upwardly through the bunker where it is discharged through the opening in the upper 120

- end thereof into the interior of the car, an operating shaft for the fan extending through the car floor and means for actuating said shaft.
- 5 2. The combination with a refrigerator car having an ice bunker therein communicating with the interior of the car at the top and bottom portions thereof whereby air circulation may be established, an ice support in the bunker, air propelling means disposed in said bunker below the supported ice thereon for accelerating said air circulation, and means for actuating said propelling means.
- 10 3. The combination with a refrigerator car having an ice bunker therein communicating with the interior of the car at the top and bottom portions thereof whereby air circulation may be established, an ice support in the bunker, a fan disposed in said bunker below the ice supported therein for accelerating said air circulation, a shaft extending from the fan through the floor of the car, an operative connection between said fan and the running gear of the car whereby the same may be rotated.
- 15 4. The combination with a refrigerator car having an ice bunker therein, means at the top and bottom of the bunker permitting air circulation between it and the interior of the car, means in the bunker for supporting ice, a drip pan arranged under said ice supporting means and having an opening therein, a fan disposed in the opening of
- said pan and mounted for rotation, and means for rotating the fan.
- 20 5. A device as set forth in claim 3 further characterized by said connection between the fan and the running gear of the car being automatically shiftable by the direction of movement of the car to maintain the rotation of said fans in one direction irrespective of the movement of the car.
- 25 6. In a refrigerator car, the combination with a car having an approximately hermetically closed storage space; of a chamber within said car having its ends in communication with said storage space, said chamber being constructed to provide free circulation of air therethrough; means for maintaining a temperature reducing medium within said air chamber in a position to interrupt the passage of air currents through the chamber, so that said currents will contact directly therewith; and means located between the storage space and the air current entrance to said chamber and adjacent to said entrance for causing air currents to pass through the chamber in a direction opposite to the course normally followed by ordinary convection currents, whereby said current of air is caused to circulate from the bottom of the storage space, through said chamber and discharged into the upper portion of the storage space.
- 30 In testimony whereof I have hereunto set my hand.
- FRANCIS M. PATTON.
